UNITED STATES PATENT OFFICE.

TOM FREDERICK GRAY, OF MANCHESTER, ENGLAND.

VALVE.

Application filed April 14, 1924. Serial No. 706,808.

This invention relates to valves, such as stop or gate valves, particularly for use with pipes or mains conveying superheated high pressure steam, and comprises an improved construction of the body or casing parts of such valves whereby the said parts are produced of light weight combined with great strength ensuring the capacity to safely withstand the stresses imposed thereon in service.

Referring to the four accompanying sheets of explanatory drawings:—

Figure 1 is an elevation, half in section, and Figure 2 is a plan, half in section, of a valve casing constructed in accordance with this invention, such casing being suitable for a junction type stop valve. Figures 3 to 6 show the separate pieces or members from which the said casing is constructed, Figure 3 being an end view of the shell, Figure 4 a sectional plan of the shell branch, Figure 5 a sectional elevation of the shell sleeve and seating ring, and Figure 6 a sectional elevation of the shell lid or cover.

Figure 7 is an elevation, half in section, and Figure 8 a plan, half in section, of another form of valve casing constructed in accordance with this invention and suitable for a stop valve of the gate or full way type.

Figures 9 to 12 show the separate pieces from which the said casing is constructed, Figure 9 being an end view of the shell, Figure 10 a sectional elevation of one of the shell branches, Figure 11 a sectional elevation of one of the branch sleeves and seating ring and Figure 12 a sectional elevation of the shell lid or cover.

The aforesaid separate pieces or members of the valve casings are made from steel discs or billets which are brought to the required shape by stamping or forging operations. Thus, with the casing illustrated at Figures 1 and 2, the shell piece *a*, which is shown separately at Figure 3, is made to a tubular form open at each end, having a flange *b* at the extremity of the portion which is of a rather smaller diameter than that of the portion having a lateral aperture

c therein to receive one end of the branch piece or member *d*. The opposite end of the said branch *d* (which is shown separately at Figure 4) has a flange *e* formed integrally therewith. Into the reduced diameter portion of the shell piece *a* there is inserted a sleeve *f* (shown separately at Figure 5) having a flange *g* formed integrally with one end of it, whereby it is detachably secured to the shell *a* by screw studs as *h*. When thus secured the face of the flange *g* is flush with the face of the flange *b* of the shell *a*. To the opposite end of said sleeve *f* there is welded the valve seating ring *i* which is preferably made of hardened steel.

The branch *d* aforesaid is welded to the shell *a*; the latter is thus provided with inlet and outlet apertures *j*, *k* for the flow of fluid. The shell is closed by the lid *l* of which a separate view is given at Figure 6. On the underside of the said lid *l* there is formed an annular groove or socket *m* to receive, as shown at Figure 1 and also by dotted lines at Figure 6, the top of the shell *a*. When the said parts are thus inserted the one within the other they are secured by welding and in the process of welding the metal is rounded at the juncture between the shell and the flange *l* as shown at Figure 1.

With the casing illustrated by Figures 7 to 12, the shell *a* has a lateral aperture as *c* in two opposite sides and in each of such apertures there is inserted and welded a branch piece as *d* having a flange *e* at one end. In each branch there is placed a sleeve *f* having a flange *g* formed integrally therewith for the detachable connection of the sleeve to the shell *a* by the screw studs *h*. Each sleeve has a valve hardened steel seating ring *i* welded thereto. The shell is formed with a closed lower end whilst its upper open end is inserted within an annular groove *m* in the lid *l* to which it is welded.

I claim:

1. A valve casing comprising a weldless cylindrical shell provided with a lateral socket, a tubular branch piece welded in said socket having a concave extremity corre-

sponding to and flush with the cylindrical interior of the shell, a lid, and an annular socket in said lid having walls contacting with and welded to the interior and exterior 5 peripheral surfaces of the shell top.

2. A valve casing comprising a weldless cylindrical shell provided with a lateral socket, a tubular branch piece welded in said socket having a concave extremity cor- 10 responding to and flush with the cylindrical

interior of the shell, a sleeve detachably secured within said branch piece, a lid, and an annular socket in said lid having walls contacting with and welded to the interior and the exterior peripheral surfaces of the shell 15 top.

In testimony whereof I have signed my name to this specification.

TOM FREDERICK GRAY.
